Inventor:
Homer A. Curtiss

UNITED STATES PATENT OFFICE.

HOMER A. CURTISS, OF MERIDEN, CONNECTICUT, ASSIGNOR TO THE
MERIDEN CUTLERY COMPANY, OF SAME PLACE.

DESIGN FOR A CAP FOR KNIVES OR FORKS.

SPECIFICATION forming part of Design No. 23,345, dated June 12, 1894.

Application filed March 9, 1894. Serial No. 503,060. Term of patent 3½ years.

To all whom it may concern:

Be it known that I, HOMER A. CURTISS, a citizen of the United States, residing at Meriden, county of New Haven, and State of Connecticut, have invented and produced a new and original Design for Caps for Knives or Forks, of which the following is a specification, reference being had to the accompanying drawing, forming part thereof, and representing my newly-designed cap in side view.

The leading feature of my design consists of a raised ornamental scroll-work or rococo border surrounding or inclosing a plain space on each side of the cap.

In the drawing *a* denotes a plain space and *b* a raised ornamental scroll-work or rococo border surrounding the same, the closed end of the cap being slightly pointed at *c* and the open end of the cap having, above the raised ornamental rococo pattern, a raised bead, *d*.

I claim—

The design for a cap for knives and forks, substantially as shown and described.

HOMER A. CURTISS.
